UNITED STATES PATENT OFFICE.

MATHEW BURRIS, OF OMAHA, NEBRASKA, ASSIGNOR OF ONE-HALF TO JOHN J. HUSTON,
OF OMAHA, NEBRASKA.

CAN AND CLOSURE THEREFOR

1,247,929.

Specification of Letters Patent. Patented Nov. 27, 1917.

Application filed January 2, 1917. Serial No. 140,082.

To all whom it may concern:

Be it known that I, MATHEW BURRIS, a citizen of the United States, residing at Omaha, in the county of Douglas and State 5 of Nebraska, have invented certain new and useful Improvements in Cans and Closures Therefor, of which the following is a specification.

This invention relates to an improvement 10 in glue cans, and has for its object to provide receptacles for containing liquid glue as merchandise packages at the time of shipment from the factory and for use thereafter, said receptacles being of such construction that they may be closed to effectively exclude air from the glue, and will 15 remain closed against accidental displacement, but having parts so arranged that the glue may be readily and conveniently removed from time to time, as may be required. While the device is described as a 20 holder for glue, it may, of course, be used as a container for liquid shellac, varnish, paint and various adhesive materials.

25 The invention consists of the novel construction, combination and arrangement of parts as described herein and claimed, and as illustrated in the accompanying drawing, wherein,—

30 Figure 1 is a side view of the device. Fig. 2 is a view in longitudinal section thereof, on line 2 2 of Fig. 3. Fig. 3 is a top plan view of the device. Fig. 4 is a side view of the closure cap.

35 Referring now to the drawing for a more particular description, numeral 5 indicates a receptacle or can for containing glue or similar adhesive, plastic or semi-plastic material, and in order that evaporation of the 40 glue may be practically prevented, and that the contents of the can may be accessible at any time for use, I provide a novel means herein to be described for closing the can, said means being of such construction that it 45 will be convenient in use and that manufacture may be economical, and that the parts will not become accidentally detached from the can.

50 Numeral 6 indicates a cylindrical neck for the container 5, said neck being connected with the inner edge of the annular ledge 7 with which the upright wall of the container is provided, said ledge being disposed substantially at right angles to the neck; 55 and at 8 are indicated a pair of segmental

flanges, these being mounted upon opposed parts and projecting inwardly of the annular ledge, the free edges *a* of said flanges being disposed adjacent to the convexed wall of the neck and providing a pair of opposed, 60 annular recesses 9, open at their ends.

At 10 is indicated a cylindrical closure cap or inverted receptacle having an imperforate top *b*. At 11 is indicated a loop substantially of inverted U-shape having a part *c* 65 disposed above the top of the closure cap to operate as a handle; and having parallel arm-strips *d* secured upon opposed parts of the cylindrical cap; the lower ends of the arms being provided with lugs 12 projecting 70 outwardly of the open end of said cap or receptacle.

In operation, the cap may have a slidable movement inwardly and longitudinally of the neck to dispose the lugs 12 upon the 75 ledge between the adjacent ends of the flanges, and by a rotatable movement of the cap, the lugs will engage in the recesses 9, the cap being of such proportions that its concave surface will engage the convexed 80 surface of the neck to exclude air; and it is obvious that the cap thereafter will not become accidentally detached from the neck by stresses directed longitudinally of the cap.

85 By means of the construction, air from the atmosphere will be excluded from the contents of the can, the cap being closely fitted upon the neck, and the closure cap may be conveniently removed from the neck 90 whenever desired. It will be noted that the only parts to which glue, paint or other adhesive substances may adhere and tending to prevent removal of the cap, is at the end of the circular wall of the neck, which is of 95 such limited extent or area that a slight force applied transversely of the neck by use of the handle *c* will effect a separation or breaking up of any adhering parts.

The adhesive liquids mentioned may be 100 shipped from the factory in the cans, these being of any suitable size or proportions, as may be desired. In order that there may be a limited degree only of friction during the rotatable movement of the closure cap, 105 the lugs are formed with ridges *e* which, on account of their engagement with the flanges 8, tend to cause the closed end of the cap to engage the upper end of the neck.

Having fully described my invention, 110

what I claim and desire to secure by Letters Patent is,—

1. In devices for the purpose described, a container formed at its upper end with a ledge and having a neck projecting upwardly from the ledge, a pair of inwardly projecting flanges on the ledge, a cap for making a closure of the neck, said cap being provided with a handle at its closed end and having a pair of outwardly projecting lugs disposed adjacent to its open end, each lug being provided with a ridge, said closure cap being adapted to have a slidable movement longitudinally of the neck for engagement of its lugs with the ledge of the container and adapted to have a revoluble movement for engaging the ridges of its lugs with said flanges to cause the closed end of the cap to be pressed against the end of the neck.
2. In devices for the purpose described, a container having a cylindrical neck and pro-

vided with segmental recesses adjacent to said neck, a cylindrical cap, a loop substantially of inverted U-shape mounted upon the 25 sides of the cap and having transversely disposed end-portions projecting outwardly of the open end of the cylindrical cap, said cap being adapted to be mounted upon the neck of the container and to have revoluble 30 movements in either direction for disposing the transversely disposed end-portions of the loop within said recesses, said end-portions of the loop being provided with projections for engaging the walls of said recesses 35 during the revoluble movements of said cap for causing a pressure of the closed end of the cap against the end of said neck.

In testimony whereof, I have affixed my signature in presence of two witnesses.

MATHEW BURRIS.
